A. E. BUGENHAGEN

CHICKEN COOP

Filed Oct. 12, 1926

By Milo B. Stevens & Co.
Attorneys

UNITED STATES PATENT OFFICE.

AUGUST E. BUGENHAGEN, OF WACO, NEBRASKA.

CHICKEN COOP.

Application filed October 12, 1926. Serial No. 141,156.

The chicken coop which is the subject of the present invention is of the type which is designed particularly for a single brood of chickens.

5 In its broadest aspects the invention contemplates a novel chicken coop which is rotatably mounted and provided with means acted upon by the wind for swinging the coop to a position so that its door will be to 10 leeward, thus to protect the interior of the coop from the wind and the elements.

A further object of the invention is to provide a novel combination and arrangement of parts whereby the device may be readily 15 cleaned; also to furnish a plurality of variously formed doors which may be selectively used to suit circumstances.

Various other objects and advantages of the invention will be readily apparent to 20 those skilled in the art as the description proceeds, reference being had to the accompanying drawings illustrating what now occurs to me as a preferred embodiment of the invention. It is to be understood, of course, 25 that various slight changes may be made in coop shown and described without, however, departing from the spirit and scope of the invention as claimed thereafter.

Referring specifically to the drawings, 30 5 denotes a base having supporting feet 6 and provided with a central bearing 5^a. The coop 7 is cylindrical in form and to its bottom 8 is bolted as at 8^a a central casting 9, the depending stud 10 of which is designed 35 to enter the bearing 5^a to thereby rotatably support the coop. A cotter pin 11 extending through a transverse hole in the stud 10 at the under side of the base holds the coop and base assembled, the coop 7 being freely 40 rotatable as stated.

The peripheral end 9^a of the casting 9 is 45 of relatively reduced diameter and bears against the upper part of the bearing 5^a. By this formation there will be relatively little frictional resistance to the turning of the coop 7. An overhanging flange 13 depends from the coop 7 and circumscribes the base 5 as clearly shown in the drawings. This flange serves to prevent the entry of dirt 50 to the area between the base 5 and the bottom 8 of the coop. The bearing 5^a and the stud 10 may thus be easily kept in a well lubricated condition and free from grit.

The doorway of the coop is indicated at 55 14 and is reached by a short approach ramp 15. Several doors of differing formation are

carried by the device and movable to operative position to close the doorway 14 depending on conditions. These doors are all shown in the perspective view Figure 1. 60 The outermost door 16 is imperforate while the immediate door 17 is perforated, and the inner door 18 is provided with a plurality of horizontally spaced vertical slats 18^a. The outer door 16 is, of course, used 65 when it is desired to completely close the doorway 14, the intermediate door 17 when it is desired to ventilate the coop, and the slatted door 18 when it is desired to keep 70 the hen confined and let the chicks out to roam around the vicinity of the coop. The doors are slidable in upper and lower slideways which are respectively denoted by reference characters 16^b, 17^b and 18^b. It is observed that these slideways are open at 75 one end as shown in Figure 1 so that any dirt that may accumulate therein can be readily scraped out making it easy to keep 80 the doors in a freely movable condition and the coop itself in a sanitary state. 80

In the drawings:—

Fig. 1 is a perspective view of the device. Fig. 2 is a horizontal sectional view of the device shown in Fig. 1. Fig. 3 is a vertical sectional view therethrough. Fig. 4 is a detail view showing the arrangement of doors. 85

The conical top 19 is removably held in place and has an opening 19^a at its apex which is surmounted by a ventilator or hood 21. The conical top is preferably formed 90 of a single sheet of metal and one end is bent laterally outward and shaped to define a vane 20 this latter constituting the means for swinging the top and the rigidly connected coop body 7 so as to maintain the 95 doorway 14 to leeward to prevent wind or rain from driving into the coop.

A bayonet slot connection is provided between the top 19 and the coop body 7 by means of rigid depending hooks 22 carried 100 by the top, certain of which engage down-turned projections 23 on the outer sides of the coop. One of the hooks 22 passes through a strap 24 also carried by the side 105 of the coop. A slight twist of the top serves to engage the hooks 22 with the projections 23. The hook 22 which engages the strap 24 prevents the top 19 from being rotated relatively of the coop 9 except to the limited extent necessary to lock the top in place. 110

In order that water may be conveniently supplied to the chicks within the coop I have

provided a water pan 25 which is insertable through a hole in the side of the coop 7. The water pan 25 is further retained in a stabilized relationship by means of guides 26 within the coop and between which the pan is positioned.

To prevent water from dripping from the conical top 19 in front of the doorway 14 I provide on either side of the vane 20 trough like deflectors 27 which carry the water off to either side. These deflectors further serve to brace the vane 20 and rigidify the top 19 as will be evident.

The operation of the device will be self evident from the foregoing description taken in connection with the accompanying drawings. The natural tendency of chicks when a rain storm comes up is to seek shelter to leeward of the coop. In ordinary stationary coops the door of the coop is just as likely to be to windward as to leeward. However, with my coop the chicks upon huddling to leeward of the same will find the doorway 14 accessible and may enter the coop. Thus, many chicks will be saved which would otherwise be killed by drowning. The coop is rodent proof, can be easily cleaned and the removable water pan insertable from without makes it possible to keep the chicks supplied with water without necessitating removal of the top or cover 19.

A feed pan 27 is preferably located on the opposite side of the coop from the water pan 25. This feed pan slides between guides 30 in the same fashion as the water pan.

What I claim is:

1. A chicken coop comprising a base having a bearing therein, a casing, the bottom of said casing having a projecting casting of a relatively small diameter the end there-

of engaging the bearing and constituting the sole point of support for the casing, a stud projecting from said casting and entering said bearing for rotatably mounting said casing upon the base, a depending skirt carried by said casing and surrounding said base whereby to prevent fouling of said bearing, said casing having a side opening therein, and wind controlled means for maintaining said opening to leeward. 50

2. A chicken coop comprising a base having a bearing therein, a casing, the bottom of said casing having a projecting casting of relatively small diameter the end thereof engaging the bearing and constituting the 55 sole point of support for the casing, a stud projecting from said casting and entering said bearing for rotatably mounting said casing upon the base, a depending skirt carried by said casing and surrounding said base whereby to prevent the fouling of said bearings, said casing having an opening therein, wind controlled means for maintaining said opening to leeward, a plurality of separate doors for closing said opening, opposed open ended slideways for guiding said doors in their movements, one of said doors having relatively large openings therein to permit the chicks to pass therethrough, and ventilating means provided in one of the 60 other of said doors. 65

3. In a rotatably mounted chicken coop having a doorway in one side, a roof provided with a wind vane above said doorway, brace members at each side of said vane, and said brace members constituting water troughs for catching rain water and deflecting it away from said doorway. 75

In testimony whereof I affix my signature.

AUGUST E. BUGENHAGEN.
